HARVEY HUBBELL, OF BRIDGEPORT, CONNECTICUT.

ADJUSTABLE REFLECTOR FOR ELECTRIC LAMPS.

964,646.

Specification of Letters Patent. Patented July 19, 1910.

Application filed February 25, 1910. Serial No. 545,894.

To all whom it may concern:

Be it known that I, HARVEY HUBBELL, a citizen of the United States, residing at Bridgeport, county of Fairfield, State of Connecticut, have invented an Improvement in Adjustable Reflectors for Electric Lamps, of which the following is a specification.

This invention has for its object to provide an adjustable reflector which may be easily and quickly attached to or removed from standard electric lamps and may be rotated to throw the light in any direction as may be required.

With these ends in view I have devised the novel reflector and means for attaching the same in place which I will now describe, referring to the accompanying drawing forming a part of this specification and using reference characters to indicate the several parts.

Figure 1 is an elevation partly broken away showing my novel reflector in place upon a standard electric lamp socket; Fig. 2 a view on an enlarged scale partly in elevation and partly in section of the attaching ring detached; Fig. 3 a similar view of the reflector neck detached; and Fig. 4 is an elevation of the contractile collar detached.

10 denotes an electric lamp, 11 a standard socket and 12 a reflector. The reflector is provided with a hole 13 through which the attaching end of a lamp bulb may be passed and in which the neck 14 is rigidly secured. This neck, which may be formed in any preferred manner as from sheet metal by press work, is shown as secured to the reflector without solder. An external rib 15 is formed near the upper end of the neck, the plane of the rib corresponding with the superficial plane of the reflector at the point of connection. The end of the neck is passed through the hole in the reflector and then the parts are secured together by turning the upper edge of the neck outward and closing it down upon the inner side of the reflector as at 16. The neck is provided at its lower end with a circumferential external rib 17 which may be formed, as shown in the drawing, by bending the metal outward, then downward and then inward.

18 denotes an attaching ring which is mounted to rotate on the circular rib and is provided with an inner threaded sleeve 19. This attaching ring is formed from sheet metal to substantially the shape shown in

cross section in Fig. 2. In addition to the threaded sleeve there is a bottom wall 20 and an outer wall 21, the three walls comprising a substantially U-shaped ring in cross section. The circular external rib 17 of the neck is received between the threaded sleeve and the outer wall of the attaching ring, said circular rib fitting within the attaching ring loosely and the attaching ring is secured to the rib by closing the upper edge of outer wall 21 over the top of the rib, as at 22 in Fig. 1, leaving the attaching ring free to rotate on the circular rib.

It is of course well understood that all standard electric lamp sockets are provided near the lamp receiving end with an external rib 23. This rib I utilize in attaching the adjustable reflector to the socket by means of a contractile collar 24 which is divided vertically across as at 25, is provided with an internal groove 26 to receive the rib on the socket shell and below the groove with a screw thread 27 which is adapted to be engaged by the threaded sleeve of the attaching ring.

The operation will be obvious from the drawing. The attaching ring is permanently attached to the neck, the neck and ring being adapted to rotate relatively to each other and the neck is rigidly attached to the reflector. In attaching the reflector to a lamp, the contractile collar is placed on the socket, the collar readily springing to allow the rib on the socket to pass into the groove in the collar, and then the threaded sleeve of the attaching ring is turned into engagement with the thread of the contractile collar, thus firmly but detachably securing the adjustable reflector to the socket.

Having thus described my invention I claim:

1. A reflector having an opening for the passage of a lamp bulb, a neck having one end bent over into engagement with the edge of said opening, and an attaching ring for a lamp socket rotatably mounted on the other end of said neck.

2. A reflector having an opening for the passage of a lamp bulb, a neck having one end bent over into engagement with the edge of said opening, the other end of said neck being provided with a circular rib, and an attaching ring for a lamp socket rotatably mounted on said rib.

3. A reflector having an opening for the passage of a lamp bulb, a neck having one end bent over into engagement with the edge of said opening, the other end of said neck being provided with a circular rib, and an attaching ring for a lamp socket rotatably mounted on said rib; said attaching ring being provided with an internal threaded sleeve.
- 10 4. A reflector having an opening for the passage of a lamp bulb, a neck having one end bent over into engagement with the edge of said opening, the other end of said neck being provided with a circular rib, and an 15 attaching ring for a lamp socket rotatably mounted on said rib, said attaching ring being provided with an internal threaded sleeve, and a contractile collar adapted to engage a lamp socket and having a threaded portion adapted to engage said threaded sleeve.

5. A reflector having an opening for the passage of a lamp bulb, a neck having one end bent over into engagement with the edge 20 of said opening, the other end of said neck being provided with an external annular rib, an attaching ring into which the ribbed end of said neck fits, said ring having a flange extending over said rib, whereby said ring

is rotatably supported, and means carried by 30 said ring for supporting a lamp socket.

6. A reflector provided with an opening for the passage of a lamp bulb, and a neck extending from said opening, an attaching ring rotatably mounted on the free end of 35 said neck and provided with an internal threaded sleeve, and a contractile collar adapted to be secured to a lamp socket and having a threaded portion to engage said threaded sleeve. 40

7. A reflector provided with an opening for the passage of a lamp bulb, and a neck extending from said opening, an attaching ring rotatably mounted on the free end of 45 said neck and provided with an internal threaded sleeve, and a contractile collar adapted to be secured to a lamp socket and having a threaded portion to engage said threaded sleeve, provided with an internal annular groove to receive a bead on a lamp 50 socket, and having a threaded portion to engage said threaded sleeve.

In testimony whereof I affix my signature in presence of two witnesses.

HARVEY HUBBELL.
